UNITED STATES PATENT OFFICE.

CLARENCE H. MORROW, OF CLEVELAND, OHIO, ASSIGNOR TO THE HOTSTREAM HEATER COMPANY, OF CLEVELAND, OHIO, A CORPORATION OF OHIO.

THERMOSTATICALLY-CONTROLLED GAS VALVE.

Application filed October 20, 1924. Serial No. 744,784.

This invention relates to thermostatically controlled valve mechanisms, such as are used for automatically controlling the supply of gas to a water heater or the like to 5 maintain a fixed predetermined temperature of the water supply.

The object of the invention is to provide a simple valve mechanism of the quick acting variety, wherein upon a reduction in 10 water temperature the gas supply is suddenly turned on full and upon an increase in water temperature to the desired value the gas is suddenly turned off, doing away with the usual lag or delay in turning on the 15 gas in such thermostatically controlled mechanisms.

A further object of the invention is to provide a simple diaphragm actuated mechanism of this kind in which the number of 20 castings and other parts is reduced and the thermostatic elements are capable of combination in the same unit with the valve members, thereby simplifying the construction and the manner of its attachment or connection to the water and gas piping system. 25

Further objects of the invention are to provide mechanism of this character utilizing thermostatically actuated parts with considerable power and motion and capable 30 of properly operating the valve parts, as well as to dispose of all gas used for operating or controlling purposes by supplying it to the pilot and reducing the quantity of gas so disposed of to thereby avoid any unnecessary yellow flame with its consequent deposit of soot. 35

Further objects of the invention are in part obvious and in part will appear more in detail hereinafter.

In the drawings, which represent one suitable embodiment of the invention, Fig. 1 is a sectional plan view on approximately the line 1—1, Fig. 2, looking in the direction of the arrows; Fig. 2 is an elevation, with the 40 lower portion of the casing broken out and in section to expose interior parts; Fig. 3 is a detail section through the lower casing member on the line 3—3, Fig. 2, looking in the direction of the arrows; Fig. 4 is an end view from the right in Fig. 1, part of the view being in section on the line 4—4, Fig. 1; and Fig. 5 is a detail section on the line 5—5, Fig. 1.

Referring to the drawings, 1 indicates a 55 portion of the wall of an ordinary water

supply reservoir or tank in which the heated water is collected, said water being heated by any suitable heater supplied by the gas current flowing through the valve controlling apparatus to be described. The wall of 60 the reservoir is suitably formed to receive a threaded extension 2 of the valve casing, said extension being hollow and containing the thermostatic elements which project into the reservoir and are sensitive to the temperature of the water therein. The thermostatic elements may be of any suitable character and in the form shown comprise an outer copper tube 3 closed at its inner end and suitably secured to the member 2, and 65 within which is located a porcelain rod or pencil 4, the outer end of which engages and operates the lever mechanism hereinafter described: 70

The casing of the valve controlling mechanism comprises essentially two members, to wit, an upper member 5, of which member 2 is an extension, and a lower member 6, said two members being faced off along annular peripherally extending meeting surfaces 7 75 between which is clamped a flexible diaphragm or bellows 8 to the central portion of which is secured a suitable valve member 9 having sufficient weight for valve actuation as will later appear. The two members 80 are, of course, securely fastened together by the usual clamping screws or bolts 10 around their peripheries. 85

The lower member 6 of the casing is cored out to form two aligned hollow bosses 11, 90 12, both threaded for the proper connection of pipe fittings thereto, the channel 11^a in member 11 serving as the inlet channel for the gas supply and communicating through an opening 13 in the wall thereof with a chamber 14 beneath the diaphragm 8. The generally horizontal wall of the member 6 is pierced at its center to form an opening surrounded by the valve seat 15, said opening 95 providing communication from chamber 14 to the outlet passage 16 in member 12, from which the gas flows through proper pipes or conduits to the burner of the heater for the water in tank 1. The purpose of the thermostatic controlling devices hereinafter described is to control the relation of valve 100 9 to its seat 15 to permit or prevent flow of gas to the heating burner. 105

The upper member 5 of the casing is provided with a cored out boss or enlargement 110

17 enclosing a chamber 17^a exposed to and lying directly above the diaphragm 8. In this chamber is located a yoke like member 18 pivoted to swing on an axis 19 and moved in one direction about said axis by a light compression spring 20, the strength of which, of course, is calibrated or adjusted with due regard for the forces which it opposes. The head of yoke 18, adjacent the pivotal axis 19, carries an adjustable socket headed screw 21, one end of which forms a fulcrum or abutment to receive the pressure of the porcelain pencil 4 due to the contraction of the copper tube 3 and the opposite end of which has a non-circular socket to receive the similarly formed end of a wrench member 22 extending outwardly through a packed joint 23 in the wall of the casing and equipped on its outer end with suitable adjusting means, such as the rigid handle 24, the outer end of which may travel over a scale 25 on the casing and serve as an indicator of the temperature to be maintained in reservoir 1.

25 At its end remote from the pivotal axis 19, the yoke 18 is provided with opposed or aligned abutment members 26 adapted by oscillating motion of member 18 around its pivotal axis to move generally back and forth along the line of the axially opposed valve members 27, 28 held by the springs 29 against their respective seats. Said valve members are located in similar oppositely disposed chambers 30, 31 respectively, closed 30 at their outer ends by caps 32. Chamber 30 communicates by a passage 33 through the peripheral portions of the members 5 and 6 and through the diaphragm 8 with the lower diaphragm chamber 14, while chamber 31 communicates by a like passage 34 with a channel 35 in a boss 36 threaded to receive a pipe 37 leading to a pilot light at the burner. In the boss 36 is a suitably adjustable needle valve 38 controlling communication between channel 35 and the lower chamber 14 beneath the diaphragm. Both of the valves 27, 28, by cooperation with their respective seats, control communication from the chambers 30, 31 to the 45 chamber 17 above the diaphragm.

50 The operation is as follows:

Let us assume that the pilot valve 38 is 55 adjusted to permit proper flow of gas by way of opening 13, chamber 14 and channel 35 to the pilot, which is burning, and that the water in tank 1 is at or above the normally desired temperature. Under these 60 conditions the flow of gas from outlet passage 16 to the burner should, of course, be shut off. Therefore, valve 9 rests upon its seat 15. The copper tube 3 is fully expanded and the pressure of the porcelain pencil or abutment screw 21 is relieved, yoke 18 is 65 swung downwardly in Fig. 1 and valve 28 is seated and valve 27 is open. Gas pres-

sure therefore flows from chamber 14 by way of passage 33 and chamber 30 to chamber 17^a above the diaphragm 8 and said diaphragm is subjected on its upper face to the pressure of the gas supply and on its lower 70 face within the seat 15 to atmospheric pressure and outside of seat 15 to the pressure of the gas supply. The valve therefore is maintained closed by the preponderance of the pressure above it and gravity over the 75 pressure below it.

If the temperature of the water in the tank 1 drops to or below a predetermined value, the copper tube 3 contracts and produces pressure of the porcelain pencil upon 80 the abutment screw 21, thereby moving the yoke 18 counter-clockwise in Fig. 1 against the pressure of spring 20 and causing its upper abutment 26 to first take up the slight clearance between it and the upper end of 85 the valve stem, thereby permitting valve 27 to seat, and to then continue its upward motion and open valve 28. This operation evacuates the gas pressure in chamber 17 by 90 way of passage 34 and channel 35 to the 95 pilot where the gas thus discharged is burned, but the quantity of gas is small,—merely the capacity of chamber 17^a or less—and has no tendency to produce a yellow flame and soot. The evacuation of pressure in chamber 17^a now subjects the diaphragm 8 to atmospheric pressure on its upper face and on its lower face within the area of the valve seat 15, and to the pressure of the gas supply on its lower face outside of valve 15. 100 This latter pressure of the gas supply now preponderates and also overcomes the gravity effect of the valve, thereby lifting the valve from its seat and immediately subjecting it to the pressure of the gas supply over 105 its entire lower area. The gas supply, of course, now passes through the opening leading to the outlet passage 16 and to the burner, which is ignited by the pilot, assuming the pilot to be burning, and produces its 110 heating effect upon the water in the reservoir. The operation is sudden with a full rush of gas to immediately turn the burner on with maximum heating effect.

The gas supply remains turned on until the temperature of the water in the tank 1 rises to the predetermined value, thereby causing expansion of the copper tube 3 and release of the pressure of porcelain pencil 4 from the abutment 21. This effect permits spring 20 to expand and again take up the clearance between its lower abutment 26 and the lower valve stem in Fig. 1, first permitting valve 28 to close and finally opening valve 27. When valve 28 closes the 125 chamber 17^a is trapped, and as soon as valve 27 opens the pressure of the incoming gas supply builds up immediately in chamber 17^a through the passage 33. The final result, effected almost instantaneously, is to 130

equalize the pressures on opposite faces of the diaphragm and permit it to drop promptly to its seat 15 and shut off the supply of gas to the burner, the parts remaining in this position until reduced temperature of the water requires additional heat. 5

With this arrangement the gas supply is turned on and shut off with small sniffs of gas from the chamber 17^a to the pilot at 10 each operation of the mechanism. The parts are simple, can be built and assembled at relatively low cost and are not likely to get out of order. They are also adjustable, particularly by adjustment of the abutment 15 screw 21 to vary the normal temperature and without liability of disarrangement of any other members. I have provided also thermostatically controlled means whereby the gas supply to the burner is permitted only 20 when the pilot is burning. That is, the thermostatic means above described for controlling the flow of gas to the burner is automatically rendered effective or ineffective according to whether the pilot is burning or 25 not.

The pilot in this case comprises the suitably apertured copper tube 39 with its one end screwed into the connector 40. In the other end of the tube 39 there is threaded 30 the steel pin or needle 41 which has its other end formed as a needle valve for engagement with a correspondingly formed seat in the wall of the connector 40. The threaded end of the needle 41 extends beyond the 35 tube 39 and is adapted for adjustment therein, a lock nut 42 being provided to secure the same in adjusted position. The pipe 37 is threaded into the opposite wall of the connector 40.

40 When the pilot is cold, the needle valve 41 is adjusted so as to engage its seat and thus close the port to the pilot. Likewise, whenever the pilot goes out, the flow of gas to the pilot is shut off, this being automatically 45 effected by the contraction of the tube 39 upon being no longer subjected to the heat of the pilot flame. Upon applying a lighting flame to the pilot, the heat therefrom causes tube 39 to expand so as to withdraw needle 50 valve 41 from its seat and permit gas to flow to the pilot. So long as the pilot remains lighted, the flow of gas thereto is permitted.

55 Referring now to the other thermostatic means for controlling the flow of gas to the burner, as above explained, it will be seen that the effective operation of this thermostatic means is in turn governed automatically according to whether the pilot is burning. For instance, when the temperature of 60 the boiler falls to or below the predetermined point and the valve 28 is opened so as to release the gas from chamber 17^a, this small quantity of gas will escape to the pilot, and valve 9 will be opened, provided the needle valve 41 is open; that is, provided the pilot 65

is burning. If however, the pilot is not burning, the automatic opening of valve 28 by reduction in temperature of the boiler, will not release the pressure of the gas in chamber 17^a since this gas, instead of escaping to the pilot, will back up and continue to exert pressure upon the upper side of diaphragm 8 so as to maintain valve 9 closed. In this way, there is precluded the danger 70 of gas flowing to the burner when the pilot 75 is not lighted.

In case the temperature of the boiler rises to or above the predetermined limit, the gas flow to the burner is automatically cut off in the manner above explained, and the pilot 80 continues to burn, as usual. Should however, the pilot go out, the flow of gas to the pilot is automatically cut off and the escape of gas is thereby prevented. 85

What I claim is:

1. Thermostatic gas valve mechanism, comprising a casing provided with opposed chambers separated by a movable abutment, a valve in one of said chambers arranged to be operated by said abutment and controlling 90 the flow of gas from its chamber to a burner, and a thermostatic element and mechanism controlled thereby for controlling movement of said abutment, both said element and mechanism being located in one of said chambers. 95

2. Thermostatic gas valve mechanism, comprising a casing provided with opposed chambers separated by a movable abutment, a valve in one of said chambers arranged 100 to be operated by said abutment and controlling the flow of gas from its chamber to a burner, and a thermostatic element and mechanism controlled thereby for controlling movement of said abutment, both said 105 element and mechanism being located in the other of said chambers.

3. Thermostatic gas valve mechanism, comprising a casing provided with opposed chambers separated by a movable abutment, 110 one of said chambers communicating with a source of gas supply, a valve in said supply chamber arranged for operation by said abutment and controlling the flow of gas from the supply chamber to a burner, valve means controlling communication between said chambers, and thermostatically controlled mechanism for operating said valve 115 means to thereby control said abutment for actuation of said valve. 120

4. Thermostatic gas valve mechanism, comprising a casing provided with opposed chambers separated by a movable element, one of said chambers communicating with a source of gas supply, a valve in the supply chamber arranged for operation by said abutment to control the flow of gas from its chamber to the burner, valve means controlling communication between said chambers, and a thermostatic element and mechanism 125 130

controlled thereby for controlling said valve means, said element and mechanism both being located in one of said chambers.

5. Thermostatic gas valve mechanism, comprising a casing provided with opposed chambers separated by a movable element, one of said chambers communicating with a source of gas supply, a valve in the supply chamber arranged for operation by said 10 abutment to control the flow of gas from its chamber to the burner, valve means controlling communication between said chambers, and a thermostatic element and mechanism controlled thereby for controlling said 15 valve means, said element and mechanism both being located in the other of said chambers.
6. Thermostatic gas valve mechanism, comprising a casing including two chambered members meeting along a plane surface, a diaphragm between said members and separating their chambers, one of said members being adapted for connection to a 20 water tank and being provided in its chamber with a thermostatic element and mechanism controlled thereby, the other of said 25

members having its chamber communicating with a gas supply, and means whereby said thermostatically controlled mechanism actuates said diaphragm to control the gas 30 flow to a burner.

7. Thermostatic gas valve mechanism, comprising a casing provided with opposed chambers separated by a movable element, one of said chambers communicating with a 35 gas supply and through a port communicating with a burner, a valve in said chamber at said port and actuated by said abutment, a thermostatic element and mechanism operated thereby, both thereof being located 40 in the second chamber and being adapted to cause operation of said abutment to control said valve, and a pilot burner communicating with said gas supply, said thermostatically operated mechanism including valve 45 means adapted to evacuate the second chamber to the pilot burner when said valve is to be opened.

In testimony whereof I hereby affix my signature:

CLARENCE H. MORROW.
